(57) **CLAIM**

The ornamental design for a cup handle connector, as shown and described.

DESCRIPTION

FIG. 1 is a left, top perspective view of a cup handle connector showing my new design;

FIG. 2 is a front elevation view thereof;

FIG. 3 is a rear elevation view thereof;

FIG. 4 is a top elevation view thereof;

FIG. 5 is a bottom elevation view thereof;

FIG. 6 is a right side elevation view thereof;

FIG. 7 is a right side elevation view of a cup handle connector connected to an illustrative weapon handle; and, FIG. 8 is a right side elevation view of a cup handle connector connecting an illustrative weapon handle to an illustrative cup.

Features shown in dashed lines within one or more of the above drawings are not part of the invention and represent an environment for the invention.
